UNITED STATES PATENT OFFICE.

FRANCIS A. CALVERT, OF LOWELL, MASSACHUSETTS.

IMPROVEMENT IN CARDING-ENGINES.

Specification forming part of Letters Patent No. 40,018, dated September 22, 1863.

To all whom it may concern:

Be it known that I, FRANCIS A. CALVERT, a resident of Lowell, in the county of Middlesex and State of Massachusetts, have made a new and useful invention having reference to machinery for carding or treating either cotton, wool, or various other fibrous materials; and I do hereby declare the same to be fully described in the following specification and represented in the accompanying drawings, of which—

Figure 1 is a top view, Fig. 2 a side elevation, and Fig. 3 a vertical and longitudinal section, of an improved carding-machine as constructed with its licker-in, made as hereinafter described, and combined with the main card-cylinder and a retainer, and provided with mechanism by which, when rotated, such licker-in will be caused not only to seize the fibrous material from the feed-rollers and lay and "work" it on the retainer, but to operate in a manner to continuously strip the rear part of the main card-cylinder of fibrous material, substantially as hereinafter explained.

The drawings do not represent all the workers and strippers, and the usual top cards and various other appliances of a carding-engine, as such devices, or any portion or portions of them, are supposed to be used with my invention whenever it may be desirable to employ them.

In such drawings, A denotes the frame for supporting the various operative parts, B being a main card-cylinder, and C another card-cylinder, which I term the "retainer."

D is a doffer or doffing cylinder of the ordinary construction. In rear of the main card-cylinder B, and just below the retainer C, there is the toothed cylinder or "licker-in" E, and in rear of that there is a pair of feed-rollers, F F, the whole of such cylinders and rollers being arranged with their axes parallel and in other respects as shown in the drawings.

The said licker-in E, instead of being covered with card-clothing, as are the retainer, the main card-cylinder, and the doffer, has teeth *a a*, made of steel, and somewhat like saw-teeth, they being raised on a band or strip, *b*, of steel, and shaped as shown in Figs. 4 and 5, the former figure being a top view and the latter a side view of a strip of such teeth. In the application of such a strip to the surface of a cylinder, *c*, composing the body of the

licker-in, it is to be wound in a helix about the curved surface of such body, and with the ends of the helix touching one another or being close together; or strips of teeth may be put on in circular rings parallel to one another, and in planes perpendicular to the axis of the licker-in, in which case the said licker-in, while in operation, should have a short reciprocating endwise motion, in order that the teeth may act on the entire curved surfaces of the main card and the retainer. When, however, the teeth are arranged in a helix, as described, a simple rotative motion of the licker-in will suffice to cause the teeth to act on the main card-cylinder and the retainer.

The directions of rotary motions of the licker-in, the feed-rollers, the retainer, and the main card-cylinder are indicated in Fig. 3 by arrows placed on them. The form and directions of the teeth of the card-clothing of the retainer, the main card, and the doffer-cylinders are also shown in Fig. 3.

On the shaft of the main card-cylinder are two grooved pulleys, G H, around each of which one of two crossed belts, I or K, runs, these belts also working respectively on pulleys L M, applied on the shafts of the licker-in and retainer.

Another pulley, N, applied to the shaft of the main card-cylinder serves to operate the doffer by means of a crossed belt, o, which goes around a pulley, P, fixed on the shaft of the doffer.

In practice the periphery of the retainer is to revolve one inch while that of the main card-cylinder turns two inches and that of the licker-in three inches. These speeds are particularly adapted for carding cotton; but in case of the machine being employed for the carding or treating of wool, the licker-in should have a much higher velocity.

The rates of speed of the retainer, the main card-cylinder, and the licker-in are not intended to be always as above mentioned, as while the periphery of the main card-cylinder is to move faster than that of the retainer, the periphery of the licker-in is to revolve faster than that of the retainer or the main card-cylinder, the rates of velocity of these parts being in proportions as may be best suited for the material to be treated.

In the operation of the machinery above described the licker-in will not only seize the fibrous material as it may be delivered by the

feed-rollers, but will carry it forward to the main card-cylinder, and thence to the retainer. In rotating alongside of the main card-cylinder the licker-in operates also to strip the latter of the fibrous material which it may carry back to the licker-in. The material so taken from the main card by the licker-in will not only be thrown by it upon the retainer, but will be combed and more or less "worked" by the licker-in, while such material may be held by the retainer and be within the sphere of action of the licker-in. The retainer will carry and deliver the material to the main card-cylinder, whose card-clothing, having a velocity faster than that of the retainer, will not only draw the fibrous material away from the retainer, but card it and prepare it for the action of the doffer. The fibrous material the doffer may fail to remove from the main card-cylinder will be likely to be taken therefrom by the licker-in. It may also be stated that the licker-in, constructed as above described, will operate as a scutcher, and not only comb but scutch the fibrous material or remove much dirt or extraneous matter therefrom. Instead of employing but one retainer to the licker-in,

there may be two or more arranged over it and with respect to one another in such manner that one may co operate with the other.

My invention has been found in practice to produce highly important and useful results.

I claim—

1. The improved carding-machine as constructed, with its licker-in made substantially as described, and combined with the main card-cylinder, a retainer, and mechanism by which, when rotated, such licker-in shall be made not only to seize the fibrous material from the feeding-rollers and transfer it to and work it when on the retainer, but operate to continuously strip the main card-cylinder at its rear, substantially as hereinbefore specified.

2. The combination of the toothed licker-in, one or more retainers, and machinery by which such licker-in may be driven or rotated at a velocity greater than that of the retainer, or that of either of them, when more than one may be employed.

F. A. CALVERT.
